PROPELLER SURFACING MACHINE

John C. Shaw, Hartford, Conn., assignor to Niles-Bement-Pond Company, Hartford, Conn., a corporation of New Jersey

Application May 6, 1937, Serial No. 141,132

8 Claims. (Cl. 90—31)

This invention relates to propeller surfacing machines and particularly to a machine for surfacing opposite faces of marine propeller blades of large size.

An object of the present invention is to provide a machine having a tracer and cutting tool, the tracer being movable over a template corresponding to a surface of the propeller blade and the tool being guided in its movements over the blade by means associated with and controlled by the tracer and its contact with the template.

Another object of the invention is to provide a turret rotatable as a unit upon a vertical axis and disposed coaxially with the propeller being finished, the turret providing means for movably mounting the supports carrying the tracer and cutting tool respectively for movements radially toward and from the axis of the turret and vertically up and down.

Another object of the invention is to provide mechanism for oscillating the turret about its axis through varying arcs depending upon the width of the propeller surface being finished, this oscillatory movement taking place simultaneously with movements vertically of the tracer and tool in accordance with the template or model being followed, feeding means being provided to successively move the tracer and tool radially a short distance either toward or from the axis between each oscillatory movement of the turret.

A feature of importance of the invention also is the application of the control mechanism and electric circuits shown and described in my Patent 1,683,581 granted September 4, 1928 to a propeller surfacing machine without substantial modification or addition.

And finally it is an object of the invention to provide a reducing means between the tracer and the tool enabling a smaller and more convenient template to be used than the propeller being finished so that the distances moved by the tracer may be materially less than those of the tool.

With the above and other objects in view, my invention consists in the features of construction and operation set forth in the following specification and illustrated in the accompanying drawings.

In the accompanying drawings annexed hereto and forming a part of this specification, I have shown the invention embodied in and adapted for a surfacing machine for propellers of extremely large size but it will be understood that the invention can be otherwise embodied and that the drawings are not to be construed as defining or limiting the scope of the invention, the claims

appended to this specification being relied upon for that purpose.

In the drawings:

Figure 1 is a complete side elevation of a propeller finishing machine made in accordance with the present invention, parts being shown in section for better illustration.

Fig. 2 is a vertical sectional view of the complete machine taken upon a plane at right angles to Fig. 1.

Fig. 3 is a plan view of the machine, one side being broken away.

Fig. 4 is a front elevation of the cutting tool and mounting therefor.

Fig. 5 is a side elevation of the parts shown in Fig. 4.

Fig. 6 is an enlarged view of parts shown in Fig. 2, this figure showing the tool carriage and its controlling mechanism for moving the carriage radially and for moving the tool spindle 20 therein vertically.

Fig. 7 is a view similar to Fig. 6 and showing the means for moving the tracer support radially and for moving the tracer bar vertically.

Fig. 8 is a detail view in section showing the tool mounting end of the tool spindle upon an enlarged scale over Fig. 5.

Fig. 9 is a detail section through the track upon which the turret revolves.

Fig. 10 is a cross sectional view taken on the plane of line 10—10 of Fig. 6; and

Fig. 11 is a cross sectional view taken on the plane of line 11—11 of Fig. 7.

In the above mentioned drawings there has been shown but one embodiment of the invention which is now deemed preferable, but it is to be understood that changes and modifications may be made within the scope of the appended claims without departing from the spirit of the invention.

Briefly and in its broadest aspect the invention may include the following principal parts: First, a fixed circular track or guideway surrounding a pit or excavation within which the propeller being surfaced may be centrally mounted; second, a turret rotatably mounted thereon; third, means to revolve the turret in either direction; fourth, supporting means within the excavation or pit so that the propeller being finished may be coaxial with the axis of rotation of said turret; fifth, a tool supporting carriage movable substantially radially on said turret; sixth, a tool head vertically movable within the carriage; seventh, a cutting tool rotatably mounted and extending from the lower end of said head; eighth, a template

mounted independently of the turret and indexable about the guideway to successive angular positions; ninth, a tracer supporting carriage movable substantially radially on said turret; tenth, a tracer carrying slide movable vertically in said latter carriage; eleventh, a tracer in the slide adapted to contact said template during operation; twelfth, means preferably in the form of electric circuits and controlled by engagement of the tracer with the template for raising and lowering the tracer and cutter in conformity therewith as the turret is oscillated between predetermined limited angular positions; and thirteenth, means to feed the tracer and cutter successively to different radial positions after each oscillatory movement of the turret.

The surfaces on opposite faces of the blades of marine propellers are generally helicoidal but depart from the exact surface of a helicoid, each side having its own modifications to provide sufficient strength in the different portions of the blade and for other purposes. The present machine does not and is not designed to generate an exact helicoidal surface on a blade but operates upon a system of copying and enlarging from reduced templates having the forms respectively of surfaces to be reproduced for each face of the blades. The templates can be originated in any manner or by any process forming no part of the present invention and preferably may have arcuate surfaces the upper edges of which conform to closely spaced portions of the desired blade surface but upon a reduced scale. As the surfaces on opposite faces of each of the blades of a propeller are similar to the others, but two templates are required for any one propeller, one for each face of the blades.

Referring more in detail to the figures of the drawings, I provide a turret 10 adapted to rotate about circular guideways 11 forming a track surrounding a pit 12. Preferably the circular ways 11 as shown in the drawings are provided on the upper horizontal surface of a massive concrete foundation 13 forming the wall of the pit 12. The excavation or pit 12 provided within the ways 11 is sufficient in diameter and depth to accommodate the maximum size propeller W to be finished upon the machine presently to be described. On the turret 10 are provided bearing rollers 14 supported on and depending from the lowermost surface, there being a number of these rollers 14 placed about the periphery of the turret 10 and bearing upon the upper surface of the circular track or ways 11. These bearings support the entire weight of the turret and parts thereon. Adjacent each of these bearing or pressure rollers 14 are opposed pairs of rollers 15 engaging the outer and inner periphery respectively of the circular ways 11. By means of the fixed circular ways 11 and the rollers 14 and 15 the turret 10 may be revolved centrally above the pit 12 about a fixed vertical axis and with minimum friction.

In order to effect rotation of this turret 10 there is provided a driving chain 16 loosely surrounding the outer surface of the circular ways 11. This chain 16 may be supported in position by means of spaced angle irons 17 outstanding from and secured to the ways 11. This chain 16 is engaged by driving sprocket wheels 18, these wheels being mounted on the lower ends of vertical driving shafts 19. Preferably, adjacent the driving sprocket wheels 18 for this turret 10 are idler wheels or pulleys 20 adjustable substantially radially in any preferred manner as indicated in

Fig. 3 so that the chain 16 may be tightened about the ways 11. By rotating the sprockets 18 by any suitable means the turret 10 will be rotated, there being locking means or sufficient friction of the chain 16 against the outer surface of the circular ways 11 to prevent rotation of the chain relative to the track.

The driving means for the sprocket wheels 18 shown in Figs. 1 and 3 may comprise a small motor 21 constantly driven in one direction, opposed clutches 22 being driven thereby and adapted to rotate a pinion 23 in opposite directions depending upon which of the clutches 22 is engaged. This motor 21 and opposed clutch mechanism 22 are in every way similar to corresponding parts shown in Figs. 13 and 14 of the drawings in my above-referred to patent. It will suffice to state that upon energization of an appropriate control circuit one or the other of the clutches 22 is energized. This drivingly connects the motor 21 with the pinion 23 through that particular clutch to rotate this pinion 23 and the turret 10 in one direction. As soon as the turret 10 has been revolved to a predetermined position that particular clutch may be deenergized and the opposite clutch energized to rotate the pinion 23 and the turret 10 in the opposite direction.

Between the driving pinion 23 and the sprocket wheels 18 is a differential mechanism 24 connected as shown in Figs. 1 and 3 to substantially radially mounted shafts 25 extending to the periphery of the turret 10 so that the load is equally divided between the shafts 25. By suitable gear connections between these horizontal radial shafts 25 and the sprockets 18 at the lower ends of shafts 19 and suitable controlling mechanism which presently will be referred to, the turret 10 may be oscillated through different angles about the central vertical axis of the machine as desired in either direction and at any desired speed. The direction and extent of oscillation will depend upon the operation of suitable switches controlled by electric circuits similar to those described in the above-referred to patent. As the controlling and operating circuits, switches, etc., for controlling the direction, speed and extent of movement of the turret 10 by the above-described connections form no part of the present invention, further description is not thought necessary.

The propeller W to be machined may be mounted centrally within the pit or excavation 12 and supported in fixed position while its entire blade surfacing operation upon one side is being completed. As shown, a central shaft 26 extends through the hub of the propeller W and has its lower end resting within a conical seat in a member 27 set into the floor of the pit 10. The securing means for the propeller are not shown or described but may be of any type facilitating removal and replacing of the propeller W within the pit 12 in opposite or inverted position.

To effect placing of the propeller W in its central position or to invert the propeller to surface the opposite sides of its blades the turret 10 first must be lifted from its position on the guideways 11. This may be readily done by lifting it bodily as by a crane, there being no clamping means necessary to hold the turret 10 in operative position other than its weight upon rollers 14 and the engagement of the rollers 15 at its periphery with the surfaces of the circular ways 11.

Preferably the template 30, the form of which is to be duplicated upon a larger scale on the blade surfaces of the propeller, as shown in Fig. 2, may be built up of a plurality of arcuate plates of relatively

thin metal such as steel sheets vertically disposed in closely adjacent concentric positions. Each plate of the template 30 has its upper edge cut away so that the surface formed by upper edges 5 of the entire group of plates will correspond to the surface desired to be reproduced in materially enlarged form on one face of the propeller blades being finished. For convenience the template 30 is made materially smaller in size than the surface 10 of the propeller being finished, one-half size being found most desirable and convenient and shown in the drawings for illustrative purposes. The radial position of the template 30, also for convenience, is chosen closer to the axis of rotation of the turret 10 than the surfaces of the propeller being machined. The variations in 15 heights of the plates of template 30 are or may be similarly reduced relative to the variations in height of the surfaces being machined. If desired, however, one scale of reduction may be used for the radial and arcuate dimensions of the template 30 relative to those of the propeller W and the same or a different scale of reduction may be used for the heights of the template surfaces 20 compared with the variations in height of the propeller W.

The template 30 is supported in position and radially disposed relative to the propeller W upon and by means of an angularly adjustable or indexable arm 31. The template supporting arm 31 may at one end be supported centrally of the propeller W and for convenience may swing about the central stud or shaft 28 which passes axially through the propeller hub. The outer end of the 25 arm 31 may be supported upon suitable roller bearings 32 and 33 engaging the fixed circular track 11 respectively upon its horizontal and vertical inner and outer surfaces. These bearings 32 and 33 may be similar in every way to the bearings 14 and 15 respectively, there being one or more rollers 32 resting on the upper or horizontal surface of the circular track 11 and one or more pairs of rollers 33 engaging the inner and outer surfaces. In addition suitable clamping 30 means (not shown) are provided for the template supporting arm 31 so that the arm 31 and template 30 may be secured in proper angular positions in accordance with the blades being surfaced in successive positions for corresponding 35 surfaces on each blade. In operation upon any surface of the propeller the arm 31 and the template 30 are retained in fixed position. When operation upon the corresponding surface of another blade is to be started the arm 31 is indexed 40 about the circular track 11 to a new radial or angular position properly disposed for the second blade and secured in that position during the cutting operation upon that surface.

The tracer 35 adapted to contact with the upper 45 surfaces or edges of the plates forming template 30 may be similar in every way to the automatic electric tracer shown in Fig. 16 of my above-referred to patent. The tracer bar or lever, however, in the present instance, is in a vertical 50 rather than horizontal position and is secured to a vertically movable slide 36 mounted within a head 37. The tracer supporting head 37 is movable along horizontal ways substantially radially disposed on the turret 10. The means for 55 controlling the radial position of the head 37 and the vertical position of the tracer slide 36 and tracer 35 may comprise electric control circuits corresponding to those used for the same purposes in the above-referred to patent. The connections between the tracer 35 and cutting tool 60

45 so that movements radially and vertically of the tracer will be transmitted in proper coordinated relation to the tool will presently be described.

The head 37 is moved step by step to successively different radial positions after each oscillatory movement of the turret 10, each radial movement causing the tracer 35 to contact with the upper edge of an adjacent template plate 30. These movements are controlled and effected by 10 electric circuits corresponding in every way to those for traversing and feeding the tracer and tool shown and described in the above-referred to patent. Fig. 7 shows the mechanism for moving the tracer 35 vertically with its slide 36 and 15 horizontally or radially on the turret 10 with the slide 36 and head 37. The slide 36 is provided with an elongated screw 38 extending longitudinally and secured to the slide 36 against endwise and rotary movement. Engaging this screw 38 is 20 a nut 39 rotatable within the head or carriage 37 but held against axial movement by any suitable means. On the nut 39 are bevel gear teeth meshing with the teeth of a companion bevel gear 40. Gear 40 is rotatably mounted in the head 37 but 25 retained against endwise movement. To rotate the gear 40 and thus raise or lower the tracer 35 there is provided an elongated splined shaft 41 within the turret 10 disposed parallel to the direction of movement of the head 37. To move the 30 carriage or head 37 radially toward and from the axis of the turret 10 there is provided an elongated screw 42 engaging within a nut 43 fixed within the carriage 37. Means to rotate the screw 42 and splined shaft 41 will presently be described. 35

The cutting tool 45 is supported within a carriage 46 substantially radially movable on the turret 10, there being suitable guideways 47 provided therefor upon the upper surface of the turret 10. To move the carriage 46 with the tool 45 thereon radially toward or from the axis of the turret 10 a screw 48 extends substantially radially of the turret. This screw is held against axial movement within carriage 46 and may be rotated 45 in either direction by means presently to be described. The screw 48 is engaged by a nut 49 fixed to and depending from the carriage.

Vertically slidable within the carriage 46 is a tool supporting slide or head 50. A screw 51, 50 extending longitudinally of the slide 50 and supported in the slide against rotation and endwise movement is engaged by a nut 52 rotatably supported within the carriage 46. By rotation of this nut 52 through the clutch driving connections and motor 53 shown in Fig. 5 the tool 45 may be raised and lowered. The motor 53 shown in Fig. 5 of the drawings controls the rotation of the nut 52 in either direction through oppositely rotating clutches of magnetic type and driving 55 connections similar to the clutches for oscillating turret 10 referred to above. The direction of rotation of the nut 52 to raise or lower the tool 45 is controlled by energizing one or the other of the clutches through the electric controlling 60 circuits described and shown in my above-referred to patent.

To raise and lower the tracer 35 and tool 45 simultaneously the motor 53 and driving means for rotating the nut 52 are connected by gears 55 70 to a spline shaft 63 disposed parallel to the direction of movement of the head 46. By suitable sprocket gears 64 and chain 65 spline shafts 41 and 63 are rotated simultaneously relative amounts. By choosing a different and longer 75

lead for the screw 51 than for the screw 38 the vertical movement of the tool 45 may be made greater than corresponding movements of the tracer 35. By this means the vertical dimensions of the tracer 30 may be materially reduced relative to the vertical heights of the propeller blades being surfaced. It will be understood that by means of controlling circuits opened and closed by contacts on the tracer 35 the screws 38 and 51 will be rotated, reversed or stopped for varying short intervals of time in accordance with the variations in elevation of the different parts of the template 30.

Screws 42 and 48 controlling the radial positions respectively of tracer 35 and tool 45 are coupled together by sprocket wheels 68 and chain 67. By choosing proper leads for the screws 42 and 48 and different diameters for gears 68 radial movements of the tracer 35 may be reduced any desired amount relative to corresponding movement of the tool 45.

As the tool carrying slide 50 and parts mounted thereon are of considerable weight, counterbalancing means therefor are provided. These means preferably are in the form of cylinders 55 secured to the slide 50 having pistons 56 secured to the carriage 46 on which the slide is supported. By admitting air to the cylinders 55 above the pistons 56 at a constant predetermined pressure the vertically moving weights may be compensated by pneumatic pressure without adding materially to the total weight carried by the carriage 46.

Within the tool carrying slide 50 is a longitudinally disposed tool rotating shaft 58 adapted to be rotated at relatively high speed as by a motor 59 mounted at the upper end of the slide 50. Motor 59 may be drivingly connected to the shaft 58 by any desired gear connections (not shown) by means of which the speed of rotation of the shaft 58 may be controlled. The lower extreme end of the shaft 58 is provided with a bevel gear 60 secured thereto in mesh with a bevel gear 61 on the inner end of an obliquely extending shaft or spindle 62 suitably supported for rotation within the slide 50. This spindle 62 has provision at its outer end for holding a cutter 45 such as a round nosed milling cutter of the type usually employed in die-sinking operations.

50 To limit the oscillatory movements of the turret 10 there may be mounted a reversing switch 70 which for convenience may be mounted on the extension of the turret 10 on which the tracer carriage 37 operates. To operate switch 70 adjustable dogs 71 may be provided in the path of movement of the switch 70. Dogs 71 may be mounted on a bracket 72 secured to the template carrying arm 31. As shown in Fig. 7, the dogs engage a T-slot provided in the upper surface of the bracket 72 along which the dogs may be adjusted and clamped in any position. With the switch 70 mounted on arm 31 the turret 10 will be oscillated between proper limiting positions for operating upon each of the blades of the propeller 65 for the reason that indexing of the arm 31 for each blade will correspondingly index the dogs 71.

Between each oscillatory movement of turret 10 the shaft 48 must be rotated to radially position the tracer 35 and tool 45 to traverse different arcuate paths over the template 30 and propeller W respectively. This rotary movement of the shaft 48 may be effected by a suitable motor 74 conveniently mounted on the outer end 75 of turret 10 and connected to the shaft 48 by

means of pinion 75 on the armature shaft of motor 74 which meshes with a gear 76 secured directly to the outer end of shaft 48.

In operation the propeller W is first located within the pit 12 centrally thereof so that its central axis will be vertical and coaxial with the track 11 upon which the turret 10 revolves. The propeller W is then secured in its central position by any appropriate means (not shown). The turret 10 is mounted in position upon its track 11 and its driving chain 16, which loosely surrounds the fixed track 11, is placed in mesh with the driving sprocket wheels 18 and the idlers 20 adjusted so that the chain will frictionally engage the outside surface of the fixed track. 15

The template 30 is then positioned on the radial arm 31 and the arm placed in proper angular position as shown in Fig. 2 with its ends respectively mounted on the central shaft 26 and on the track 11. The arm 31 is then adjusted to the proper angular position above one of the blades being finished so that the tracer 35 will engage a portion of the template 30 when the tool 45 is in position to operate on the portion of the propeller blade W corresponding to the portion of the template 25 engaged by the tracer.

The cutting operation can now take place during which the turret 10 is slowly oscillated about the track 11 back and forth while the tracer 35 passes over arcs about the surface of the blade 30 being finished. After each oscillatory motion of the turret in each direction the tracer 35 and cutter 45 may be moved radially outward. These oscillatory and radial movements of the tracer 35 and tool 45 alternate until the entire surface of 35 the blade has been traversed and its surface made to conform to that of the template but upon an enlarged scale.

To start the cutting operation on another blade the arm 31 and the template 30 thereon 40 are indexed angularly about the axis of the turret 10 so that the template 30 will be disposed above another blade to properly locate the tracer 35 for operation of the cutter 45 on the second blade. This blade may then be finished in the 45 same manner as the first blade and the remaining blades may then be successively finished by again indexing the arm 31 and oscillating the turret 10 between different angular positions. After one face of each of the blades has been 50 finished the turret 10 is lifted off its track 11 and the propeller W inverted, thus presenting the opposite sides of the blades to the cutting tool 45. As the opposite sides of the propeller blades are or may be of different contour this side is finished 55 with its own template different from and replacing the first template on the radial arm 31.

What I claim is:

1. A propeller surfacing machine comprising in combination, means to support a propeller in fixed position, a turret mounted for rotation coaxially with said propeller, a tool carriage movable substantially radially on said turret, a tool side vertically movable on said carriage, a tracer supporting carriage on said turret, a vertically movable tracer therein, a model conforming to a plurality of arcuate contours of a blade and supported in fixed position below said tracer, means controlled by contact of said tracer with said model for raising and lowering said tool slide, 70 means to oscillate said turret during operation of said tool, and means to move said tracer and tool slide in predetermined relation to each other. 65

2. A propeller surfacing machine comprising in combination, means to support a propeller in 75

- fixed position, a turret mounted for rotation coaxially with said propeller, a tool carriage movable substantially radially on said turret, a tool slide vertically movable on said carriage, a tracer supporting carriage on said turret, a vertically movable tracer therein, a model conforming to a plurality of arcuate contours of a blade and supported in fixed position below said tracer, means controlled by the contact of said tracer with the model for raising and lowering said tool slide, means to oscillate said turret during operation of said tool, and means to periodically move said tracer and tool slide short distances radially in predetermined relation to each other. 5
15. 3. A propeller surfacing machine comprising in combination, means to support a propeller in fixed position, a turret mounted for rotation coaxially with said propeller, a tool carriage movable substantially radially on said turret, a tool slide vertically movable on said carriage, a tracer supporting carriage on said turret, a vertically movable tracer therein, a model conforming to a plurality of arcuate contours of a blade and supported in fixed position below said tracer, means controlled by the contact of said tracer with the model for raising and lowering said tool slide in accordance with movements of said tracer, means to oscillate said turret during movements radially of said tool to traverse said tracer and cutter respectively over said model and propeller, and means to advance said tracer and cutter to successively different paths over said model and propeller. 20
25. 4. A propeller surfacing machine comprising in combination, means to mount a propeller and cutter for relative movement whereby said cutter may traverse the entire surface of a blade of said propeller, a model and tracer mounted for relative movement whereby said tracer always engages a portion of the model corresponding to the portion of the propeller engaged by the cutter, and means to advance and retract said cutter and tracer in accordance with the contour of said model during the traversing respectively of the model and propeller. 30
35. 5. A propeller surfacing machine comprising in combination, a pit within which a propeller may be centrally mounted and retained in fixed position, a circular track surrounding and concentric with said pit, a turret rotatable on said track, a rotatable cutter on said turret mounted for radial and vertical movements, a model conforming to a plurality of arcuate contours of a blade and mounted in predetermined position relative to said propeller, a tracer mounted on said turret for arcuate movements over said model, and means to oscillate said turret to traverse said cutter over the propeller. 35
40. 6. A propeller surfacing machine comprising in combination, a pit, means to centrally position and retain a propeller therein, a circular track surrounding said pit, a turret rotatable upon said track coaxial with said propeller, a sprocket chain surrounding said track, a sprocket wheel on said turret engaging said chain, and means to rotate said sprocket wheel in opposite directions to oscillate said turret. 40
45. 7. A propeller surfacing machine comprising in combination, a pit, means to centrally position and retain a propeller therein, a circular track surrounding said pit, a turret rotatable upon said track coaxial with said propeller, a sprocket chain surrounding said track, a sprocket wheel on said turret engaging said chain, adjustable idler wheels on said turret engaging said chain whereby the chain may be tightened about said track, and means to rotate said sprocket wheel in opposite directions to oscillate said turret. 45
50. 8. A propeller surfacing machine comprising in combination, a pit, means to centrally position and retain a propeller therein, a circular track surrounding said pit, a turret rotatable on said track, bearing rollers on said turret contacting with the upper surface of said track, rollers on said turret engaging the inner and outer surfaces of said track, a sprocket chain surrounding said track, driving means on said turret engaging said track for rotating said turret, and means to disengage said driving means from said track whereby said turret may be removed from said track. 50

JOHN C. SHAW.
